LIFT TRUCK

John M. Squier, Dennis E. Fales, and Richard F. Mc-
Intosh, Battle Creek, James G. Balmer, Birmingham,
and Paul J. Petlewski, Detroit, Mich., assignors to Clark
Equipment Company, a corporation of Michigan

Application May 3, 1954, Serial No. 30,313

Term of patent 14 years

(Cl. D14—3)

FIG. 1

Des. 175,804

PAGE 2

FIG. 2

FIG. 3

Fig. 1 is a perspective view of a lift truck, showing our new design;

Fig. 2 is a side elevational view thereof; and

Fig. 3 is a rear end elevational view thereof.

The dominant features of our design reside in the portions illustrated in solid lines.

We claim:

The ornamental design for a lift truck, as shown and described.
